HANDLE FOR A MOTOR DRIVEN TOOTHBRUSH

Seymour Troy, 15 Southfield Road, Mount Vernon, N.Y.

Filed Mar. 28, 1963, Ser. No. 74,180

Term of patent 7 years

(Cl. D9—2)

FIG. 1.

FIG. 2.

FIG. 3.

FIG. 4

FIG. 5.

FIG. 1 is a plan view of a handle for a motor driven toothbrush, showing my new design.

FIG. 2 is an elevational view of one side thereof, the sides being symmetrical.

FIG. 3 is a bottom view thereof.

FIG. 4 is an end view thereof taken in the direction of the arrow designated FIG. 4 in FIG. 2.

FIG. 5 is an end view thereof taken in the direction of the arrow designated FIG. 5 in FIG. 2.

I claim:

The ornamental design for a handle for a motor driven toothbrush, as shown and described.
